HINGED CLIP FOR TOY WOODEN BLOCKS

James A. Hummel, 6903 Carey Lane, Osseo, Minn.
55369, and Richard B. Hummel, 1917 Belmar Way,
Upland, Calif. 91786

Filed Oct. 5, 1972, Ser. No. 295,140

Term of patent 14 years

Int. Cl. D21—01
U.S. Cl. D34—15 GG

FIG. 1

FIG. 2

FIG. 3

FIG. 4

FIG. 1 is a perspective view of a hinged clip for toy wooden blocks showing our new design;

FIG. 2 is a top plan view;

FIG. 3 is a side elevational view; and

FIG. 4 is an end elevational view.

The top and bottom surfaces are identical, and front and side views will, also, be identical to rear and opposed side views.

We claim:

The ornamental design for a hinged clip for toy wooden blocks, as shown.
